UNITED STATES PATENT OFFICE.

WILLIAM H. GOLDING, OF CHELSEA, MASSACHUSETTS.

PRINTING-PRESS.

SPECIFICATION forming part of Letters Patent No. 451,681, dated May 5, 1891.

Application filed September 10, 1888. Serial No. 285,017. (Model.)

To all whom it may concern:

Be it known that I, WILLIAM H. GOLDING, a citizen of the United States, residing at Chelsea, in the county of Suffolk, State of Massachusetts, have invented certain new and useful Improvements in Printing-Presses, of which the following is a specification, reference being had therein to the accompanying drawings.

10 This invention relates to printing-presses of that class known as "oscillating."

The objects of the invention and the construction, operation, and advantages thereof will appear in the following description, and 15 the novel features will be particularly pointed out in the claims.

Referring to the drawings, Figure 1 is a side elevation of the complete press. Fig. 2 is a rear elevation of the inking mechanism 20 and the bracket for supporting the same on the press. Fig. 3 is a detail in perspective of the ink-well, the parts being shown as opened or partially separated from each other. Fig. 3^a is a front view of the parts of the ink-fountain just after their separation. Fig. 4 is a side elevation of the platen and frame. Fig. 4^a is a plan of the platen-gages. Fig. 5 is a plan of the oscillatory platen-frame. Fig. 6 is a plan of the rear surface of the platen 25 with the throw-off mechanism and with the gripper-shaft and cam arranged therein. Fig. 7 is a detail in perspective, on an enlarged scale, of a portion of the throw-off mechanism. Figs. 8 and 9 are respectively longitudinal and vertical sections of the throw-off wedge. Fig. 10 is a side elevation of the ink-disk pawl-carrying bracket. Fig. 11 is a perspective, and Fig. 12 a front elevation, of that 30 portion of the roller-frame which is provided with a pawl-bracket-operating cam.

Like letters refer to like parts in all the figures.

A represents the base of the machine, and it is provided between its ends with a box A', the front wall A² of which is pivoted, as at A³, to serve as a door, a knob A⁴, and any ordinary spring-bolt or other fastening A⁵ is provided, it may be, at one or both of the edges of the door to take into an aperture or 40 apertures A⁶ in the side wall of the box, whereby the door can be retained in a closed position.

Within the base and above the box are drawer-cleats B', on which the bottom board of the drawer B slides. The front wall B² of the drawer is provided with a shoulder B³, having semicircular or other recesses to receive the ends or journals C' of ink-rollers C. In this instance, also, the front wall B² is provided with an integral drawer-pull B⁴, the front wall being made of a single casting, which projects to the rear in the form of a bracket, as at B⁵, through which screws or bolts are passed into the bottom of the drawer to secure the front wall in position. The rear wall is made like the front wall, with the exception that the drawer-pull B⁴ is omitted from the casting.

By the construction thus far described the space between the end walls and the base is utilized not only in the form of a box, but also with a drawer especially adapted for the reception and retention of the ink-rollers by supporting them solely by their journals, so that the body of the roll is not injured and all the rolls within the drawer can be kept free from dust and clean.

Upon the base A and by means of knife-edge projections A^{6x} is mounted a treadle D, it being provided with a laterally-projecting lug-embracing pocket D' on each side, so that by means of a connecting-rod D² and crank-arm D³ the main shaft D⁴ of the press may be rotated. This shaft is mounted in bearings D⁵ arranged on the top of the base and at each side thereof, and carries a pinion D⁶, which meshes with the master-gear D⁷ of the press. A crank-shaft D⁸ is mounted in the frame E, which is connected to the base by bolts E'. The gear D⁷ is keyed to the crank-shaft. A crank-rod F is mounted on a pin F', projecting from the outer surface of the gear D⁷, and serves by the pivotal connection at F' with the roller-frame G to oscillate said frame on its pivotal bearing G' in the frame E. The rear cross-bars G² of the roller-frame G have formed thereon, or it may be attached thereto, branches G³, arranged substantially at a right angle to each other and connected by a vertically and laterally curved slotted bridge G⁴, the slot G⁵ of which is designed to operate the pawl-carrying bracket H by means of a pin H' thereon, which projects into said slot.

I' represents the ink-disk-supporting bracket, which is bolted at I to the top of the bed of the press and substantially at the center transversely of the platen. The bracket 5 I' is of such a shape as to bring the surface of the disk J in line with the roll-track E² of the frame E. The spindle J' of the disk passes through bearings H² H³, formed in the pawl-bracket, and in bearings I² I³ of the 10 disk-supporting bracket I.

K represents a chase-latch, which is pivoted at K' at the top of the bed, and is projected beyond its pivot and connected with a coil-spring K², which is attached to the lug K³, 15 extending from the ink-disk bracket, so that by said spring the latch is held in a position to retain the chase against the bed and under, so as to permit of raising the latch for the removal of the chase. The upper end of the 20 pawl-bracket is bifurcated to form two arms H⁴ and H⁵, the latter extending beyond the former so as to form an obstruction against which a stop L' on the double pawl L may abut. These projections L' are on the tooth 25 portion of the pawl, of which there are two, and between the two there projects a reversing-arm L², which is whenever during a movement of the ink-disk J operated by the lug J², projecting from the lower surface of the disk 30 J, (see Fig. 10,) so as to throw one of the teeth L³ of the pawl out of operation and to bring the opposite tooth L³ into operation with a series of lugs J³, (see Fig. 2,) formed on the under surface of the disk, and constituting 35 what may be termed the "rack-teeth" of the disk, as they alone operate in connection with the pawl proper.

The bridge G⁴ on the roller-frame is curved vertically for the purpose of maintaining the 40 pin H' and its anti-friction roller H⁴ when employed constantly within the slot G⁵, and the lateral curvature of the bridge and of the slot is for the purpose of oscillating the pawl-bracket H, in order that the pawl may travel 45 over the rack-lugs J³ in one direction and be brought against one of said lugs when traveling in the opposite direction, so as to give motion to the ink-disk to secure a proper distribution of the ink upon the ink-rollers as 50 they travel over the same. (See Figs. 10 to 12.) When during the return-stroke of the bracket H, in which it is carried over one or more of the rack-lugs J³, the arm L² reaches the lug J², then said arm serves to swing the 55 pawl L on its pivot L⁴ so as to turn the tooth, which, during the preceding platen-stroke, moves the disk away from, so as to pass over the adjacent rack-lug J³ and to bring the opposite tooth L³ toward the disk and in line 60 with its adjacent rack-lug J³, so that said opposite tooth becomes for a time the operating tooth of the pawl, whereby the disk is rotated in the opposite direction. There being but one reversing-lug J³, it is apparent 65 that the disk will be reversed at the end of each substantially complete rotation.

M represents the ink-fountain, which is

mounted on the riser M' and secured by the bolt M² to an arm M³, which terminates in clamps M⁴ M⁵, adapted to embrace the bracket I' above its bearing I², and to be removably secured to said bracket by means of a bolt M⁶, passing through both of the clamps, which are extended beyond the bolt and adapted to abut against each other, as at M⁷. The object 70 of the riser M' is to elevate the ink-fountain and its delivery-roll above and out of contact with the base of the ink-disk, in order that the ink shall be conveyed directly from the fountain to the ink-roll of the press instead of 75 to the ink-disk.

The fountain-roll M⁸ is provided with a rigidly-mounted ratchet-wheel M⁹, and on the shaft M¹⁰ of the roll there is loosely mounted a pawl-lever M¹¹, carrying a pawl M¹². A connecting-rod M¹³ extends from the free end of the pawl-lever M¹¹ to a lug extending from the roll-frame G at such a distance from its pivot as to give the desired throw of the connecting-rod and to the bolt-lever. The connecting-rod is slotted, as at M¹⁴, to give a 80 period of rest between the movements of the pawl-lever.

The ink-fountain M embodies novel features of construction. It has a cover M¹⁵, a roll-cover M¹⁶, made as a part of and projecting from one of the roll-bearing brackets M¹⁷. It has also an opposite roll-bearing bracket M¹⁸. These brackets are perforated, as at M¹⁹, for the reception of thumb-screws M²⁰, which are seated in lugs M²¹, formed at opposite sides of the fountain, as seen best in Fig. 1, so that two of said thumb-screws serve to bind the parts together to permit of their separation for cleaning and to regulate the quantity of 95 ink delivered by the roll M⁸. The bracket M¹⁸ has projecting therefrom and seated therein rigidly a pivotal rod M²², which passes through the upper ends of standards M²³, projecting upwardly from the fountain-bed. Now it will 100 be seen that the single pivot-rod M²² serves to connect the cover M¹⁵, the roll-cover M¹⁶, and the two roll-supporting brackets M¹⁸ pivotally with the fountain-body as said rod passes through lugs M²⁴, formed on the cover 105 M¹⁵, which lugs are arranged inside of the standards M²³, while the brackets M¹⁷ and M¹⁸ are arranged outside of said standards.

In Figs. 3 and 3^a the parts are shown as 110 opened away from each other. Now by drawing the bracket M¹⁸ away from the standards M²³ the said parts may be entirely separated from each other for cleaning purposes. The roll M⁸ fits ink-tight within the brackets and beneath its cover M¹⁵ and against the outlet of 115 the fountain-body, so that when the parts are closed the quantity of ink delivered by the roll may be regulated by means of the screws M²⁰.

Referring now to Fig. 1, N represents a connecting-rod connected operatively with the 120 connecting-shaft D⁸ by the divided box N', and extends and is pivotally connected at O' to the rock-arms O, (shown in dotted lines,) which are pivoted in the frame at O². The 125

means for pivotally connecting the rod N to the rock-arms O may be readily extended from one to the other of the rock-arms O; or said arms may be constructed with an integral cross-bar similar to the cross-bar G² of the roll-frame. Links O³ serve to connect the rock-arms with the oscillatory platen-support P by being pivoted in ears P', cast or otherwise formed at its lower extremity. The platen-support is a strong, heavy, substantially U-shaped casting having a strengthening cross-bar P², extending from one arm of the U to the other, and having strengthening-flanges P³ under each arm around the curves of the U, as clearly shown in Fig. 4.

P⁴ represents the pivot-bearing of the support. The head of the support is provided with strengthening-ribs P⁵ and with perforations P⁶, in which are seated the platen-adjusting bolts P⁷, which have a set-nut P⁸.

Q represents the platen proper, which is cast with the usual strengthening-ribs Q' and with pivot-lugs Q² for the support and operation of the gripper-shaft R', to which is secured the grippers R and the gripper-cam R², extended beyond its pivot, as at R³, for the connection of the gripper-spring R⁴, the other end of which is secured to any suitable fixed part. Thumb-screws R⁵, Fig. 1, project through collars R⁶ of the gripper-fingers and into a slot R⁷ in the gripper-shaft formed for longitudinal adjustment of the grippers upon the shaft. The platen is also provided with an apertured lug Q⁸, through which a thumb-screw Q⁴ passes, and is threaded in a nut Q⁵, arranged above two longitudinal slotted platen-gages Q⁶, each of which is provided at its upper end and on its lower surface and within its extreme edge with a curved depending lug Q⁷, against which the lower edge of the paper rests when arranged on the gage. (See Figs. 4 and 4^a.) The gages may be adjusted by turning either the head of the thumb-screw or the nut Q⁵ and by sliding the gages along on the bolts to determine the distance of their projection upwardly on the platen, and also by swinging the gages on the bolt to determine the distance which they shall be from each other. In this adjustment the curvature of the lug Q⁷ is advantageous in giving a uniformly smooth surface for supporting the sheet in all positions of adjustment of the gages.

The throw-off mechanism involves the following construction: The platen proper is connected with the platen-support solely by springs S, which are at one end secured to the support by bolts S' entering apertures P⁷ in the support. The opposite end of each spring is secured to the platen by bolts S², entering apertures S^{2x} formed in the platen. Q⁸ represents ordinary platen-clamps. At one end of the platen and entering its edge there is seated a pivot T' for throw-off lever T. At its free end this lever is provided with a lug T², adapted to take upon a slight projection T³ formed on the edge of the platen, and

serving to removably connect the free end of the lever against accidental displacement, and yet permit of its quick and ready detachment. Between the free end and the pivot of the lever T there projects inwardly between the platen and platen-support a rod T⁴. A link T⁵ is mounted for reciprocation on the rod T⁴. At its opposite end it is perforated at a right angle to the bearing for the rod T⁴, for the reception of a rod U', projecting from the cam-frame U of the throw-off mechanism. This cam-frame is pivoted to the under surface of the platen, as at U², and is provided with recesses U³, having its walls beveled inwardly from the lower to the upper surface of the frame for the reception of similar beveled wedges V. These wedges are beveled lengthwise and have enlarged heads V', which, when the platen is in position to take an impression from type on the bed, rest upon the bolts P⁷ of the platen-support. The inner surface V² of each wedge is plain and takes bearing on the true faces of lugs Q⁹, (see Fig. 4,) formed at the intersection of two of the strengthening-ribs Q' of the platen. Now it will be observed, as thus far described, that as the platen is in position to take an impression when the free end of the lever T is connected therewith it can be quickly thrown off as it is approaching the bed by simply grasping the handle of the free end of the lever and quickly drawing it toward the operator, the direction of the movement of the platen assisting the operation. As the lever is drawn toward the operator, the cam-frame is rotated on its pivot, thereby withdrawing the thicker ends of the wedges from between the platen and the bolts in its support. The platen is thrown away by means of the springs above described. During this movement of the cam-frame the link T⁵ travels toward the lever on the pin T⁴ by reason of the curved path of the pin U' about the pivot U² from its end toward the frame U until it reaches a point opposite the pivot of the frame, when it travels away from said frame on the pin U.

In Fig. 7 a portion of the frame U and its pin U', the lever, and a portion of the platen are shown in the relative positions which they occupy when the platen is "on." By this construction of throw-off mechanism there is but one part to be seized by the operator, and the platen is practically locked beneath when "on" or "off." Of course it is understood that the springs S permit of the change of the relative positions, its relative support, and at the same time maintain a parallelism which would not be secured by the mere pivotal connection, and yet have such a connection constructed to maintain parallelism between the platen and bed when the platen is on. Such parallelism will be immaterial when the platen is off. Any ordinary pivotal connection of the platen and support can, if desired, be substituted for the spring-connection herein disclosed, so that the novel features of my

throw-off mechanism are not limited in this particular.

It now only remains to follow the operation of the parts which give motion to the platen and its support. The crank-shaft D^8 is rotated by the gear D^7 , which is keyed thereto, and said shaft gives oscillation to the rock-arms O , thus giving oscillation to the platen-support by means of the intermediate links O^3 . When the platen is parallel with the bed, the parts approach a straight line, extending from the center of the pivot O^2 to about the point, Fig. 1, whereby rebounding of the platen is prevented and a smooth reversal of the direction in its travel—that is, away from the bed—is secured. The casting (the lugs L' on the teeth L^3 of the double pawl L) renders the adjustment of the pawl to co-operate with the frame H^4 and the rack-lugs a simple matter, in that after being cast and while assembling the parts the lugs L' simply require, by grinding, a reduction to such a length as to permit of a swinging movement of the bolt on its pivot sufficient only to allow the tooth of the pawl to drop behind the rack-lug, and at the same time to limit said movement so that the extreme end of said tooth shall not come into contact with the disk between the lugs. The arm L^2 also serves as a weight or a counter-balance to maintain the idle-tooth of the double pawl away from the disk until said arm reaches the reverse-lug J^2 . The ink-fountain supporting-arm is slotted, as at M^{31} , to permit of such an adjustment as will cause the inking-roll M^8 of the fountain to project more or less over the ink-disk. Each ink-roller rod G^7 is bent to embrace the roller-journal and at its opposite end is flattened to fit the end of a guide-bar G^8 , secured at a side of the rod upon the ink-roller frame. This construction prevents the rod G from turning in its bearings.

What I claim is—

1. A drawer for ink-rollers, having opposite walls thereof provided with ink-roller-journal-receiving depressions and with lugs for the connection of the wall of the drawer with its bottom, substantially as specified.
2. A wall for an ink-roller drawer, having ink-roller-journal receptacles and having integral lugs for connecting the wall to the adjacent part of the drawer, the whole formed as a single casting, substantially as specified.
3. In a press of the class described, an oscillating platen-support, a rock-arm connected by a link to the same, a crank-shaft connected to the rock-arm, and gearing connecting the treadle with the crank-shaft, substantially as specified.
4. In a press of the class described, a substantially U-shaped platen-support adapted to be extended beyond its point of suspension and connected by links pivoted to the arms of the support, and two rock-arms, in combination with a crank-shaft pivotally connected with the rock-arms, the latter being pivoted at a point below the point of suspen-

sion of the platen-support, whereby the operative parts approach a straight line when the platen is in a vertical position, substantially as specified.

5. In a press of the class described, a pivoted support extended beyond its pivot, rock-arms pivoted at a point below the pivot of the support, links connecting the free end of the rock-arms with the support, a crank-shaft and a connecting-rod extending from the same to the rock-arms and connected therewith at a point between their free ends and their pivots, substantially as specified.

6. The combination, with an ink-disk and ink-disk-supporting bracket of a printing-press, of a pawl-carrying bracket mounted for pivotal movement and provided with an arm extending beyond its pivot, and a slotted cam arranged upon the ink-roller frame to engage a pin on the pawl-carrying bracket, and means for oscillating said frame, substantially as specified.

7. The combination, with an ink-disk having a series of rack-lugs and a pawl-reversing lug, of a double-toothed pawl having an arm arranged in the path of the reversing-lug of the disk, substantially as specified.

8. An ink-disk provided with a pawl-reversing lug, substantially as specified.

9. A double-toothed ink-disk-operating pawl having an arm projecting midway between the teeth of said pawl and having its outer end at substantially right angles to its body portion, substantially as specified.

10. The combination, with the roller-frame of a printing-press and with a cam thereof, of an oscillating pawl-carrying bracket, a double pawl arranged therein and provided with a reversing-arm, and an ink-disk provided with rack-lugs and a reversing-lug, substantially as specified.

11. In a printing-press, an ink-fountain the cover, roller-support, and roller-cover of which are removably connected by a single pivotal rod, substantially as specified.

12. In a printing-press, an ink-fountain having its cover, the cover for its roller, and the brackets for supporting said roller and the body of the fountain connected by a single rod, substantially as specified.

13. In a printing-press, an ink-fountain having one of the journals of its roller removably mounted in a roll-supporting bracket, the latter being retained in operative position by the ink-supply-adjusting screw, substantially as specified.

14. In a printing-press, an ink-fountain having the roller-supports and roller-cover thereof secured in operative position by the ink-supply-adjusting-screw thereof, substantially as specified.

15. In a printing-press, an ink-fountain having a roll-cover and roll-supporting bracket formed in a single casting, substantially as specified.

16. In a printing-press, an ink-fountain having roll-supporting brackets pivotally con-

- nected to the fountain and one longitudinally adjustable and secured in operative position by the ink-supply-adjusting screw, substantially as specified.
- 5 17. In a printing-press, an ink-fountain body provided with standards apertured for the reception of a rod and having its cover pivoted to said rod, substantially as specified.
- 10 18. In a printing-press, an ink-fountain body having standards apertured for the reception of a rod and roller-supporting brackets mounted on said rod, one rigidly and the other removably, substantially as specified.
- 15 19. In a printing-press, a roll-cover adapted on its under surface to fit the periphery of the roll and terminating at one side in a bracket provided with a roll-bearing, which bracket is fitted to the end of the roller, provided with an aperture for an adjusting-screw
- 20 and with a bearing for its pivotal connection with a fountain-body, substantially as specified.
- 25 20. The combination, with an ink-disk-supporting bracket, of an ink-fountain-supporting arm terminating in clamps which are adapted to embrace said bracket, substantially as specified.
- 30 21. The combination of a pawl-carrying bracket having a projecting arm, as at H, and a double-toothed pawl the teeth of which swing in a common plane with said arm, substantially as specified.
- 35 22. The combination, with the platen and its support, of yielding means arranged between and substantially parallel with the platen and support and connected at its ends thereto, substantially as described.
- 40 23. The combination, with a platen and its support, of a movable series of wedges interposed upon curved lines between the platen and support, and means for changing the position of the wedges, substantially as specified.
- 45 24. The combination, with a platen and its support, of an interposed pivot-frame carrying wedges having enlarged heads, substantially as specified.
- 50 25. The combination, with a platen and its support, of springs connecting the one with the other and of an interposed series of wedges beveled lengthwise and having enlarged heads designed to rest upon the bolts of the platen-supports, and means for operating the same, substantially as specified.
- 55 26. The combination, with a platen and its support, of an interposed frame carrying
- wedges and connections for the frame and lever pivoted to the under surface of the platen, substantially as specified.
27. The combination, with a platen and its support, the latter provided with adjusting-bolts and the former with bearing-surfaces substantially opposite said bolts, of a frame carrying wedges and adapted to move the same between said bolts and surfaces, substantially as specified.
28. The combination, with a platen and its support, the latter having adjusting-bolts and the former having bearing-surfaces, of a pivoted frame carrying curved wedges, substantially as specified.
29. The combination, with a platen and its support, of an interposed wedge-carrying frame, a rod projecting over said frame, a lever having a rod projecting at a right angle from the first-mentioned rod, and a link connecting and adapted to slide on the rods, substantially as specified.
30. As a means for operating a throw-off mechanism of a press, a lever having a rod, a partially-rotating device for moving the platen to and fro, a rod extending from said device, and a link connecting the same with the rod of the lever, substantially as specified.
31. The combination, with a platen and its support, of a frame having recesses with inclined walls and with beveled wedges adapted to fit said recesses, substantially as specified.
32. In combination with the platen of a press, a lever pivoted to the platen, throw-off mechanism, the parts thereof with the exception of said lever being arranged in rear of the pivot of the lever with relation to the direction of the movement of the platen toward the bed, and connecting devices arranged between the throw-off mechanism and the lever, whereby a simple movement of the free end of the lever in a direction opposite to the movement of the platen serves to throw the same off, substantially as specified.
33. The combination, with the platen of the printing-press, of a bearing, as V, for the platen, having a flat surface for holding the strain of the impression and an inclined portion for throwing off the impression, substantially as specified.
- In testimony whereof I affix my signature in presence of two witnesses.
